United States Patent Office

Des. 226,555
Patented Mar. 27, 1973

226,555

BOTTLE CAP

Heinz Weber, Dorval, Montreal, Canada, assignor to
Quality Oil Corporation, Dorval, Montreal, Canada

Filed Apr. 2, 1971, Ser. No. 130,871

Term of patent 14 years

Int. Cl. D9—07

U.S. Cl. D9—278

FIG. 1

FIG. 2

FIG. 3

FIG. 4

FIG. 5

FIG. 6

FIG. 1 is a perspective view of a bottle cap showing my new design;

FIG. 2 is a perspective view with the captive cap in an open position;

FIG. 3 is a side elevational view on a reduced scale with the captive cap in a closed position;

FIG. 4 is a top plan view thereof;

FIG. 5 is a bottom plan view thereof; and

FIG. 6 is a sectional view taken on the line 6-6 of FIG. 4.

I claim:
The ornamental design for a bottle cap, as shown.
